UNITED STATES PATENT OFFICE.

HARRISON C. MATTHEWS, OF ABBOTT, TEXAS.

SAFETY CAR-NET.

1,242,834.

Specification of Letters Patent.

Patented Oct. 9, 1917.

Application filed May 31, 1917. Serial No. 171,985.

To all whom it may concern:

Be it known that I, HARRISON C. MATTHEWS, a citizen of the United States, residing at Abbott, in the county of Hill and State of Texas, have invented certain new and useful Improvements in Safety Car-Nets; and I do hereby declare the following to be a full, clear, and exact description of the invention, such as will enable others skilled in the art to which it appertains to make and use the same.

This invention relates to improvements in nets for cars whereby trainmen traveling over the top of the car may be protected from falling between the adjacent cars.

An object of this invention is to provide a safety device adapted to be attached to freight cars, the same closing the space between adjacent cars to prevent the passage of a person to the wheels of a car should he fall or be thrown from the roof of a car.

A further object of this invention is to provide a guard, which will automatically adjust itself to the distance between the cars when the train is rounding a curve so that the space between the cars will be normally closed to the trainman.

A still further object of this invention is to provide a safety net of this character, which will be simple, practical and comparatively inexpensive in construction, and one that can be manufactured and sold at a low cost.

With these and other objects in view, the invention consists in the novel combination and arrangement of parts hereinafter more fully described and set forth in the claims hereto appended.

In the drawings:

Figure 1 is a side elevation illustrating the ends of adjacent cars equipped with my novel safety net,

Fig. 2 is a top plan view of the same,

Fig. 3 is a fragmentary end elevation of a car illustrating the safety net secured thereto,

Fig. 4 is a side elevation to more fully illustrate the manner in which the netting is secured to the device,

Fig. 5 is a longitudinal sectional view of the attaching plate and tubular member to illustrate the plunger actuating therein,

Fig. 6 is a perspective view of the outer rail or guard of the safety net.

Like numerals of reference designate corresponding parts in all the figures of the drawings.

Referring to the drawings, the numeral 1 designates a box car or freight car of any ordinary construction and to which my improved safety net is adapted to be applied.

My improved safety net comprises in its construction, the rectangular attaching or supporting plates 2, which are secured to the ends of the car at a spaced distance apart intermediate the ends thereof by suitable bolts 3 or other suitable fastening means. A cylindrical member 4 is formed integrally with one face of the plates 2 and extends horizontally therefrom, and is adapted to have located therein, a coiled spring 5. The outer open ends of the members 4 have bushings 6 fitted therein.

A flexible netting 7 is constructed of any woven material and secured by its side edges between the opposing faces of the cylindrical members 4 when the same is secured to one end of a car at a spaced distance apart, thus closing the space between the end of the cars and the outer ends of the cylindrical members 4, as shown in Fig. 2.

A guard rail 8 rectangular in cross section constructed of suitable metal has secured to one face adjacent each end, the horizontally extending plunger rods 9, which rods 9 are adapted to be slidably arranged in the tubular or cylindrical members 4, and the rods have secured adjacent their inner ends, pins 10, which are adapted to abut the outer ends of the springs 5, so as to permit the springs to be moved inwardly when pressure is applied to the front face of the rail 8, thereby compensating for and permitting the bar to assume different angular positions, so that the guard is rendered automatically adjustable to accommodate itself to the changes with relation to the adjoining ends of the cars when the cars are traveling upon straight and curved portions of the track, during which the adjusting motion of the plungers may move to different distances within the cylindrical members 4. The springs take up and absorb all shocks and jars, which may be sustained by the guard rails 8 and also normally urge the plunger rods outwardly in an extended position permitted by the distance between the ends of the cars so as to always close the

intervening space or gap for the prevention of accidents of the character described.

Supporting rings 11 are slidably arranged upon each of the rods 9 and have secured thereto, a suitable netting of woven material designated 12. The side edges of the netting 12 are secured to the rings 11 so that when the rods 9 are moved inwardly against the tension of the springs, the netting 12 may collapse and be readily extended when the springs 5 urge the rods outwardly in their extended positions again.

It is to be understood that the nettings are to be secured to each end of the car to close the gap between the same and the adjacent car. It is also to be understood that the device is so secured to the ends of the cars as not to interfere with the operation of the brakes thereof or with the proper handling of the car.

What is claimed is:

1. In a safety attachment for cars, the combination with a car, plates secured to the car, cylindrical members carried by the plates, springs located in the cylindrical members, a guard rail, plunger rods carried by the guard rail and movable in the cylindrical members, springs located in the cylindrical members and surrounding the plunger rods of the guard rail, and a netting material secured to the cylindrical members and plunger rods, as and for the purpose specified.

2. In a safety attachment for cars, the combination with a car body, attaching plates secured to the ends of the body at a spaced distance apart, cylindrical members formed integrally with and extending at right angles from the plates, coiled springs located in the cylindrical members, a guard rail, plunger rods secured to and extending at right angles from the guard rail adjacent each end thereof, said plunger rods slidably arranged in the cylindrical members and bearing against the springs, a foraminous material secured to the opposing faces of the cylindrical members, rings slidably arranged on the rods, and a foraminous

material secured to the rings, as and for the purpose specified.

50

3. In a safety attachment for cars, the combination with a car body, rectangular attaching plates secured to the ends of the car at a spaced distance apart, cylindrical members formed integrally with and extending at right angles from one face of the plates, springs located in the cylindrical members, a guard rail, plunger rods secured to and extending at right angles from one face of the guard rail adjacent each end thereof, said plunger rods slidably arranged in the cylindrical members and bearing against the springs, said springs normally urging the guard rails outwardly to compensate for the intervening space between the adjacent car ends, and a foraminous body secured between the opposing faces of the cylindrical members and to the plunger rods.

55

4. In a safety attachment for cars, the combination with a box car, of a pair of rectangular attaching plates secured to the ends of the box car at a spaced distance apart, cylindrical members secured to and extending at right angles from one face of the attaching plates, coiled springs arranged in the cylindrical members, a foraminous body secured by its ends to the opposing faces of the cylindrical members, a guard rail rectangular in cross section, plunger rods secured to one face of the guard rail and extending at right angles therefrom, said plunger rods slidably arranged in the cylindrical members and bearing against the springs, means carried by the guard rail and engaging the springs for normally urging the guard rail extended, and a plurality of rings slidably arranged on the plunger rods, and a foraminous body secured to the rings, as and for the purpose specified.

60

In testimony whereof I affix my signature in presence of two witnesses.

HARRISON C. MATTHEWS.
